Primary Examiner—Jeffrey Asch*Attorney, Agent, or Firm*—Knechtel, Demeur & Samlan[57] **CLAIM**

The ornamental design for a “magazine rack”, as shown and described.

DESCRIPTION

FIG. 1 is a perspective view of a “magazine rack” showing my new design;

FIG. 2 is a left side elevational view thereof, the right side elevational view being identical thereto;

FIG. 3 is a top plan view thereof;

FIG. 4 is a front elevational view thereof;

FIG. 5 is a rear elevational view thereof; and,

FIG. 6 is a bottom plan view thereof.
